UNITED STATES PATENT OFFICE

156,561

DESK

Imas W. Rice, Aurora, Ill.

Application September 24, 1948, Serial No. 148,747

Term of patent 14 years

(Cl. D33—7)

To all whom it may concern:

Be it known that I, Imas W. Rice, a citizen of the United States, residing at Aurora, in the county of Kane and State of Illinois, have invented a new, original, and ornamental Design for a Desk, of which the following is a specification, reference being had to the accompanying drawing, forming part thereof.

Figs. 2, 3 and 4 are front, side and top plan views respectively thereof.

I claim:

The ornamental design for a desk, as shown.
IMAS W. RICE.
